Primary Examiner — Karen E Kearney*Assistant Examiner* — John M Otte(74) *Attorney, Agent, or Firm* — McAndrews Held & Malloy, Ltd.**CLAIM**

The ornamental design for a display screen or portion thereof with graphical user interface, as shown and described.

DESCRIPTION

The FIGURE is a front view of a display screen or portion thereof with graphical user interface, showing our new design.

The dashed broken lines showing portions of the display screen or portion thereof with graphical user interface are for environmental purposes only and form no part of the claimed design.
